UNITED STATES PATENT OFFICE.

JOHN REPETTO, OF PHILADELPHIA, PENNSYLVANIA.

METALLIC CRATE.

No. 873,086.

Specification of Letters Patent.

Patented Dec. 10, 1907.

Application filed May 23, 1906. Serial No. 318,282.

To all whom it may concern:

Be it known that I, JOHN REPETTO, a citizen of the United States, and a resident of Philadelphia, county of Philadelphia, and 5 State of Pennsylvania, have invented certain new and useful Improvements in Metallic Crates, of which the following is a full, clear, and complete disclosure.

My invention relates to packing and storing vessels, and particularly to those which are skeleton in form and are made up of metallic parts.

The object of my invention is to provide such a vessel which is light in weight, strong, 15 durable and sanitary, all of the parts being readily accessible for washing or cleaning or the like.

A further object of my invention is to provide a crate which is especially suitable for 20 the transportation of bottles, jars or like receptacles, the construction of the same being such that the said bottles and jars may be retained within the crate by virtue of their frictional engagement with the parts surrounding the same.

With these objects in view, my invention consists in the details of construction and manner of operation set forth in the following description and accompanying drawings, in which like reference characters refer 30 to corresponding parts.

In the drawings, Figure 1 is a perspective view of my invention illustrated as a crate; Fig. 2 is a perspective view of a fragmentary 35 portion of one of the wires forming the bottle receptacles, a section of rubber tubing being shown in dotted lines; Fig. 3 is a fragmentary portion of a modified form of one of the wires forming a part of the receptacles; Fig. 4 is a 40 transverse section of the crate; Fig. 5 is a fragmentary longitudinal section of one of the corners of the crate taken on line 5—5 of Fig. 4 and Fig. 6 is a fragmentary longitudinal section of another corner of the crate 45 taken on line 6—6 of Fig. 4, showing a portion of a bottle in position in its receptacle, and Fig. 7 is a perspective view of a fragmentary portion of one of the wires forming the bottle receptacles.

50 The body portion or frame of my crate is made up of light structural iron, the end portions being duplicates of each other and the side portions also being duplicates of each other. Each end portion consists of an 55 angle bar bent up into the form of a U, hav-

ing sides and bottom pieces 1, 2 and 3 respectively. This angle bar is L-shaped in cross section and consequently presents transverse and longitudinal webs. To form the lower side edges of the frame I connect 60 the two U-shaped end bars by longitudinal angle bars 4—4, the latter being bolted at their respective ends to the lowermost portions of the longitudinal webs of the side pieces 1—1 and 2—2 respectively.

To form the upper, side and end edges of the frame I connect the upper extremities of the webs of the bars 1—1 and 2—2 respectively by the bars 6—7 and 8—9, the latter four bars being U-shaped in cross section and forming a rectangular frame bolted adjacent to its corner portions to the horizontal and transverse webs of the vertical end pieces 1—1 and 2—2 respectively. These top U-shaped bars have upper and lower webs extending 70 inwardly, and present a vertical base portion 75 towards the exterior of the crate.

Connecting the transverse webs of the end pieces 1—2 and 1—2 respectively and the longitudinal webs 1—1 and 2—2 respectively are the end slats 14—15 and the side slats 14'—15'. Connecting the horizontal webs of the bottom edges 3—3 of the end pieces are the longitudinal slats 16, and connecting the horizontal webs of the side pieces 80 4—4 are the transverse slats 18, the latter passing directly over the longitudinal slats and being bolted to the same to form an open-work floor of the crate. The horizontal webs of the end pieces 3 and the transverse slats 14—15 are connected by the vertical slats 17, each of the latter being bolted 85 to its respective seat and web, and likewise the horizontal webs of the side pieces 4 and the longitudinal slats 14'—15' are connected 90 by the vertical slats 17'—17'. Connecting the respective end and side slats 14—15 and 14'—15' are the longitudinal and transverse wires 20, kinked upwardly and downwardly 95 respectively where they intersect or cross each other, as indicated at 25 and 26, thus forming rectangular openings arranged in vertical pairs, one above the other. A portion 100 of each wire between two of its kinks has another lateral kink covered with a short section of rubber tubing or other yielding material. This lateral kink prevents the tubing from being displaced. Attached to the ends and side portions of the frame are 105 the sheet metal plates 30—31. These plates 110

are fastened to the exterior vertical webs respectively of the U-shaped bars 6, 7, 8 and 9, their upper edge portions extending the entire length of the said bars, so that they pass between the bars and the upper portion of the webs 1—1 and 2—2 respectively. The webs, plates and U-shaped bars are bolted together at each end of the latter by a single bolt passing through all three parts. Between the web portions and along the upper edges of the said plates are fastened the beads 10—10 and 11—11 respectively, the beads, plates and bars all being bolted together at intervals by single bolts, as illustrated in Figs. 4 and 5.

The sheet metal plates 31—31 are secured at intervals to the slats 15' on the sides of the crate by single bolt connections, each of which is integral with the transversely extending wires 20, as shown in Figs. 4 and 6. This construction is effected by shouldering down the extremities of the wires into shank portions 12, as shown in Figs. 3, 4 and 6 and striking up the end portions into a head after the parts are assembled. The sheet metal portions are cut away from their bottom edges for the sake of procuring lightness, but preferably are cut in such a manner as to leave a strip across the upper portion thereof to enable the same to receive marks of identification. The edges of the said portions, after they are free from contact with the bar 15', are curled over a wire rod 28 into a bead 29, thus strengthening the edge and presenting a round portion which may be grasped by the hand. The end plates 30—30 may be constructed and secured in the same manner as the side plates 31—31, but preferably I form them as illustrated in Figs. 1, 4 and 5, wherein the lower edge is secured only at one point. Otherwise, the plates 30—30 are constructed in the same manner as plates 31—31. The sheet metal portions may also be cut away within their edges, forming orifices, and the edges of these orifices may be curled in the same manner as the edges hereinbefore described, or a cast metal handle may be bolted within the same, as shown at 19—19. The upper, end and side slats 15—15' are located about midway of the height of the crate, thus all the parts making up the receptacles for the bottles are in the lower portion of the crate, while the upper portion is entirely free and unobstructed, leaving the upper portion of the bottles, which are most fragile and susceptible to accident, also free from contact with any portion of the crate. The upper portion is also protected by the metallic side and end walls or plates. Thus, my crate is skeleton in form where the bottles are less susceptible to accident, but is inclosed by walls where they are most susceptible. The edges of the slats 18 are beveled, as shown at 18', as are also the edges of the slats 17—17', as at 13—13'.

Referring to Fig. 4, it may be seen that the lower portion of the usual bottle is rounded to a slight degree, and when it is resting on the slats 16 and the web portions of the piece 4, the bevel 18' permits the same to make 70 a closer fit. Instead of having the wires 20—20 covered with sections of rubber tubing, as is variously illustrated, I may utilize any other yielding material, or I may utilize wire kinked as described, without any yielding material whatever.

The above construction has been described as applying to a crate for containing bottles, but the same may be used as a crate for containing other receptacles, such as bottles, jars and the like, and while it is desirable that the said receptacles should have frictional contact with the surrounding parts, yet this is not always essential. The size and shape of the receptacles can be accommodated to 85 the shape of the article to be contained therein by bending the wires to any desired configuration, or by so shaping the rubber tubing as to accomplish this end. The herein-described device is called a crate, but it is 90 obvious that I may utilize the frame portion for a casing by constructing the same so that the longitudinal and transverse wires will be eliminated. The cut away portions are illustrated as V-shaped, but I may cut away the 95 plates in any other manner, provided that I do not destroy the strength and protection given by such parts. I have illustrated and described two sets of slats, but it is obvious that I may use any number suitable to the 100 size and requirements of the crate.

Throughout the specification I have used various terms to designate the several parts, such as structural iron, angle bars, U-shaped bars, slats, beads, etc., yet I do not wish to 105 limit myself to the exact construction of these parts herein shown, but reserve the right to utilize any of the well known equivalents thereof, provided the same are within the scope of my invention, as set forth in the 110 appended claims.

Having thus described my invention, what I claim and desire to protect by Letters Patent of the United States is:

1. A metallic crate, comprising a skeleton 115 frame having its vertical and lower edges formed of angle bars and its top edges formed of U-shaped bars, sides and bottom slats secured to the webs of the angle bars, and sheet metal plates fastened to the webs and slats 120 around the upper portion of the sides, the said plates having serrations on lower edges and beads formed on the edges of such serrations.

2. A metallic crate, comprising a skeleton 125 frame having its vertical, bottom and top edges formed out of structural bars, each end thereof having its vertical and bottom edges bent out of one single piece, transverse slats fastened to the webs of said vertical pieces, a 130

sheet metal plate secured to the top bar of the end portions and also secured to one of the transverse slats, the said plates having serrations on their lower edges and beads 5 formed on the edges of such serrations.

3. In a metallic crate, a sheet metal plate secured on one of its edges to a part of said crate and having its opposite edge serrated and beaded and secured to another part of 10 the crate.

4. A metallic crate, having its edges made up of structural bars, and the lower portion of its sides, ends and bottom made up of slats crossing each other, and fastened at their extremities to the webs of said bars, the upper portions of said sides and ends being formed of sheet metal plates, having their upper edges secured to the top edge of the crate and their lower edges secured at intervals to 15 the top slats, the said plates having triangular serrations on their lower edges and beads formed on the edges of such serrations.

5. A metallic crate, having its edges made up of structural bars, and the lower portions 25 of its sides, ends and bottom made up of slats crossing each other and fastened to the webs of said bars in combination with wires extending transversely and longitudinally of the crate, and having their extremities fastened to the slats, forming skeleton receptacles, the said wires being kinked up and down at their intersections, covered with rubber tubing intermediate their kinked portions, and being struck up into edges, to 30 keep said rubber tubing in place.

6. In a metallic receptacle, a crate comprising superimposed and substantially rectangular meshes formed from longitudinally and transversely extending wires kinked up 40 and down at their intersections, the said wires being covered with yielding material intermediate their intersections and being struck up into edges to keep said yielding material in place.

45 7. In a metallic receptacle, a crate comprising superimposed and substantially rectangular meshes formed from longitudinally and transversely extending wires, the said wires being covered with rubber tubing on 50 the sides of the meshes and being struck up into edges to keep said rubber tubing in place.

8. A metallic crate comprising vertical and horizontal angle irons forming the marginal edges thereof, upper and lower slats secured to the webs of the opposite vertical angle irons to form the lower portions of the sides and ends of the crate, slats secured to the webs of the opposite lower horizontal angle irons to form the bottom of the crate, said latter slats being extended vertically at opposite ends to meet the said horizontal slats, wires extending transversely and longitudinally of the crate between the said upper and lower horizontal angle irons to form the receptacles, the upper portions of the sides and ends being formed of sheet metal plates, having their upper 65

slats and secured thereto to form receptacles, and serrated plates forming the upper portions of the sides and ends of said crate.

9. A metallic crate comprising vertical and horizontal angle irons forming the marginal edges thereof, upper and lower slats secured to the webs of the opposite vertical angle irons to form the lower portions of the sides and ends of the crate, slats secured to the webs of the opposite lower horizontal angle irons to 70 form the bottom of the crate, said latter slats being extended vertically at opposite ends and being fastened to the said horizontal slats, wires extending transversely and longitudinally of the crate between the said upper and lower horizontal slats and secured thereto to 75 form receptacles, and sheet metal plates forming the upper portions of the sides and ends of the crate, said plates being fastened at their upper edges to horizontal angle irons of the structure and having their lower edges 80 serrated and fastened to the said vertical and horizontal slats at their intersections.

10. A metallic crate comprising vertical and horizontal angle irons forming the marginal edges thereof, slats secured to the webs of the opposite vertical angle irons to form the lower portions of the sides and ends of the crate, slats secured to the webs of the opposite lower horizontal angle irons to 85 form the bottom of the crate, said latter slats being extended vertically at opposite ends to meet the said horizontal slats and wires extending transversely and longitudinally to 90 form receptacles, the ends of some of said wires passing through intersections of the said vertical and horizontal slats to bind the same together and to support the said wires.

11. A metallic crate comprising vertical and horizontal angle irons forming the marginal edges thereof, horizontal slats secured to the webs of opposite vertical angle irons to form the lower portions of the sides, slats secured to the webs of opposite lower horizontal angle irons to form the bottom of the 95 crate, said latter slats being extended vertically at opposite ends to meet the said horizontal slats, sheet metal plates forming the upper portions of the sides and ends of the crate, said plates being fastened at their upper edges to horizontal angle irons of the structure and having their lower edges serrated, and wires extending transversely and longitudinally of the crate to form receptacles, the ends of some of said wires passing through 100 the intersections of said horizontal slats with the said vertical slats and said plates to bind the same together and to support said wires.

12. A metallic crate having its edges made up of structural bars, and the lower portions 105 of its sides, ends and bottom made up of slats crossing each other, and fastened at their extremities to the webs of said bars, the upper portions of said sides and ends being formed of sheet metal plates, having their upper 110

edges secured to the top edge of the crate and their lower edges secured at intervals to the top slats.

13. A metallic crate, having its edges made up of structural bars, and the lower portions of its sides, ends and bottom made up of slats crossing each other, and fastened at their extremities to the webs of said bars, the upper portions of said sides and ends being formed of sheet metal plates, having their upper edges secured to the top edge of the

crate, and their lower edges secured at intervals to the top slats, the said plates being spaced away from said slats between their secured portions.

In witness whereof, I have hereunto set my hand this 21st day of May 1906.

JOHN REPETTO.
